UNITED STATES PATENT OFFICE.

THOMAS HENRY McCUALEY, OF CALGARY, ALBERTA, CANADA.

CAR-BRAKE-OPERATING MECHANISM.

1,285,281.

Specification of Letters Patent. Patented Nov. 19, 1918.

Application filed November 16, 1917. Serial No. 202,333.

To all whom it may concern:

Be it known that I, THOMAS HENRY McCUALEY, a citizen of the Dominion of Canada, residing at Calgary, in the Province of Alberta and Dominion of Canada, have invented a new and useful Car-Brake-Operating Mechanism, of which the following is a specification.

The device forming the subject matter of this application is a brake operating mechanism for street cars and like vehicles, and the invention aims to provide novel means whereby, when the brakes are released, energy may be stored up in a spring, to facilitate a quick setting of the brakes.

It is within the province of the disclosure to improve generally and to enhance the utility of devices of that type to which the present invention appertains.

With the above and other objects in view, which will appear as the description proceeds the invention resides in the combination and arrangement of parts and in the details of construction hereinafter described and claimed it being understood that changes in the precise embodiment of the invention herein disclosed can be made within the scope of what is claimed without departing from the spirit of the invention.

Figure 1 shows in front elevation, a brake setting mechanism embodying the improvements hereinafter described;

Fig. 2 is a side elevation of the structure shown in Fig. 1;

Fig. 3 is a rear elevation of the structure shown in Fig. 1;

Fig. 4 is a rear elevation showing a modified form of the invention, parts appearing in section; and

Fig. 5 is a side elevation of the device shown in Fig. 4.

Referring to Figs. 1, 2 and 3, the numeral 1 denotes the floor of a car. Fixed to and rising from the floor 1 is a post 2, a back plate 3 being attached to the post. A standard 4 is spaced from the post 2 and is connected to the back plate 3 by means of cross bolts 5 and 6. The parts above alluded to constitute a supporting structure for various movable elements to be described herein-after.

A horizontal main shaft 7 is journaled for rotation in the post 2, the back plate 3 and the standard 4, the shaft 7 carrying at one end a hand wheel 8. A drum 9 is mounted

to move with the hand wheel 8 with the shaft 7. An endless chain or belt 10 is trained around the drum and around a sheave 11 journaled at 12 on a foot plate 14 attached by securing elements 15 to the post 2, so that the vertical position of the sheave 11 may be changed, the chain belt 10 being loosened or tightened as a consequence.

At 16 there appears an upright guide in the form of a rod, the lower end 17 of the guide being attached to the floor 1. The upper end of the guide 16 is fashioned into a U-shaped handle 18 attached as shown at 19 in Fig. 3 to the post 2. A traveler 34 is mounted to reciprocate vertically on the guide 16 and is provided with a laterally extended pedal 35 to which a dog 36 is pivoted as shown at 37, the dog being forked or otherwise constructed at its free end to coöperate adjustably and releasably with one run of the chain belt 10.

The numeral 20 denotes a casing through which the main shaft 7 passes, the casing having lateral ears 21 mounted on the bolts 6 and held thereto by set screws 22 or otherwise. Disposed within the casing 20 is a coiled spring 23, one end of which is secured to the main shaft 7, the other end of which is secured as shown at 24 to the casing 20.

A pinion 25 is secured to the main shaft 85 between the casing 20 and the back plate 3 and meshes into a combined gear and ratchet wheel 26 carrying a drum 27, the wheel and the drum being journaled on a shaft 28 mounted in the post 2 and the standard 4. The numeral 29 indicates a spacer on the shaft 28 and interposed between the drum 27 and the standard 4 so as to hold the gear wheel 26 in mesh with the pinion 25, the spacer being in the form of a hub on the drum 27, if desired. One end of a flexible element 30 is attached as shown at 31 to the drum 27, the flexible element extending downwardly through the floor 1 and around a direction changing idler 32 journaled on a frame 33 carried by the floor. The flexible element 30 is operatively connected, in any desired manner, with the brakes (not shown).

A pawl 38 is pivoted at 39 to the back plate 3 and is adapted to coöperate with the combined gear and ratchet wheel 26, the pawl being located below said wheel, and being so mounted that it tends to gravitate out of engagement with the wheel. An angu-

lar rod 40 is pivoted to the pawl 38 and is mounted to slide in one or more guides 41 on the post 2. The lower end of the rod 40 is pivoted to a lever 42 fulcrumed at 43 on the post 2. A strip 44 is attached to one edge of the post 2 and is provided with an upstanding end 45, constituting a guide for directing the foot of an operator upon the pedal of lever 42. A rod 46 is pivoted to 10 the pawl 38 and carries, at its lower end, coacting adjusting nuts 47. A releasing rod 48 is mounted to slide vertically in guides 49 on the post 2 and is provided at its upper end with a handle 50. An abutment 51 15 is secured to the rod 48, a compression spring 52 surrounding a portion of the rod 48, one end of the spring engaging the abutment 51, and the other end of the spring engaging one of the guides 49. The lower 20 end of the rod 48 is supplied with a laterally extended eye 53 through which the rod 46 passes slidably, the nuts 47 on the rod 46 being disposed below the eye 53.

A pawl 54 is pivoted at 55 to the back 25 plate 3 and coöperates with the combined gear and ratchet wheel 26, the pawl being located below the said wheel, and being so mounted that it tends to gravitate out of engagement with the wheel. An angular 30 rod 56 is pivoted to the pawl 54 and extends downwardly to a pedal or lever 57, to which the rod is pivoted, the pedal being fulcrumed as shown at 58 on the post 2.

In practical operation, the person operating 35 the mechanism hereinbefore described steadies himself by grasping the handle 18. The pedal 35 is pushed downwardly by foot pressure, the traveler 34 moving downwardly on the guide 16. When the pedal 35 40 is thrust downwardly, the dog 36, coacting with the chain belt 10, causes the chain belt 10 to ride over the sheave 11 and rotate the main shaft 7 and the hand wheel 8, by means of the drum 9. When the main shaft 7 is 45 rotated as above described, the pinion 25 is rotated, the same imparting rotation to the gear wheel 26 and the drum 27, the flexible element 30 being operated, and the brakes being released. When the shaft 7 is rotated, as aforesaid, the spring 23 is wound 50 up and put under tension, energy thus being stored, to be used in setting the brakes quickly. In order to hold the tension thus secured in the spring 23, the pedal or lever 55 42 is depressed, raising the rod 40 and causing the pawl 38 to coact with the combined gear and ratchet wheel 26. When the pawl 38 is raised as above described, the rod 46 slides through the eye 53 on the rod 48 until 60 the nuts 47 are disposed closely below the eye.

When it is desired to set the brakes, the pawl 38 is released from the gear and ratchet wheel 26. This operation may be 65 brought about by giving the hand wheel 8

a slight turn or jar; but ordinarily, the rod 48 is slid downwardly by means of the handle 50, the eye 53 on the rod coacting with the nuts 47 on the rod 46, and the latter element serving to draw the pawl 38 70 out of engagement with the combined gear and ratchet wheel 26. When the wheel 26 is set free, as above described, the spring 23 reacts on the shaft 7 and rotates the drum 27 by means of the pinion 25 and the 75 gear wheel 26, the chain or flexible element 30 being actuated to set the brakes, the operation above described taking place with great rapidity. If desired, the hand wheel 8 may be given a turn or two to set up the 80 brakes tightly, in case the desired friction has not been produced by the action of the coiled spring 23. If it is desired to hold the brake pressure, then the pedal 57 is tilted, the rod 56 raising the pawl and moving the 85 same into engagement with the wheel 26. The pawl 54 may be disengaged from the wheel 26 by giving the hand wheel 8 a slight turn. In the modified form shown in Figs. 4 and 5, the numeral 59 marks a 90 U-shaped post corresponding to the post 2. A vertical main shaft 60, represented in Fig. 3 by the part 7, is journaled in the post 59. A spring casing is shown at 61, the function of the part 20 being recalled. A 95 frame 62 is mounted on the post 59. Journaled in the frame 62 is a horizontal shaft 63 carrying a hand wheel 65 and a drum 64. A chain belt 75 is trained around the drum 64 and corresponds with the chain belt 10. 100 The shafts 63 and 60 are operatively connected by intermeshing beveled pinions 66, a ratchet wheel 67 being secured to the shaft 63. The ratchet wheel 67 coöperates with a dog 68 corresponding to the part 38, the 105 dog being operated by means of a rod 69 corresponding to the rod 46, but extended downwardly for engagement with a pedal (not shown). The numeral 70 denotes a rod 110 like the rod 48 hereinbefore described and having an eye 71 through which the rod 69 passes, there being an abutment 72 on the rod 69 and adapted to coact with the eye 71. At 73 there appears a dog which is fulcrumed on the frame 62, the dog 73 having 115 the functions of the dog 54 hereinbefore described. The dog 73 is controlled by a rod 74, represented in Fig. 3 by the rod 56. The guide 76 has the functions of the guide 16 of Fig. 1.

The operation of the structure last above described does not differ materially from the operation of the structure first set forth in this specification, minor changes having been made in order that the shaft 60 may 125 be disposed vertically, it being observed that the shaft 7 is horizontally disposed in Fig. 1.

It will be understood that the traveler 34 may be raised and lowered, it being possible to engage the dog 36 with one run of the 130

chain belt 10, at any desired height. In this way, the vertical throw of the pedal 35 may be regulated.

Having thus described the invention, what 5 is claimed is:—

1. In a device of the class described, a support; a main shaft journaled therein; an idler on the support; a belt trained around the shaft and the idler; a guide; a traveler 10 mounted to reciprocate on the guide; an adjustable connection between the traveler and one run of the belt; a spring; means for securing one end of the spring; means for operatively connecting the other end of 15 the spring with the shaft whereby the spring will be tensioned when the traveler is operated; means for holding the shaft releasably against rotation under the action of the spring; and a brake setting mechanism 20 controlled by the shaft.

2. In a device of the class described, a support; a main shaft journaled therein; an idler on the support; a belt trained

around the main shaft and around the idler; a guide; a traveler mounted to reciprocate 25 on the guide; an adjustable connection between the traveler and one run of the belt; a spring; means for securing one end of the spring; means for connecting the other end of the spring with the main shaft 30 whereby the spring will be tensioned when the traveler is operated; a gear wheel journaled on the support; brake setting mechanism operatively connected with the gear wheel; a pinion on the main shaft and meshing 35 into the gear wheel; and individually operable pawls carried by the support and coacting with the gear wheel to limit the rotation thereof in opposite directions.

In testimony that I claim the foregoing 40 as my own, I have hereto affixed my signature in the presence of two witnesses.

THOMAS HENRY McCaULEY.
